ABSTRACT

A reversible pawl particularly applicable to rotary toothed members associated with turnstiles is provided not only with the normal return spring tending to position the pawl neutrally but a secondary spring preferably with high damping characteristics, so arranged that in a rest position the pawl is biassed in one sense of operation or the other according to which was the last operational movement of the toothed member.

TURNSTILE OR LIKE MECHANISMS

This invention relates to a reversible pawl-controlled mechanism in which a toothed rack or like element is movable through a certain range of movement or a series of ranges, and within any one range is pawl-controlled so as to be irreversible, being reversible between the end teeth of two consecutive ranges.

More particularly the invention is concerned with reversible turnstile mechanism in which a rotatable element has to be permitted to turn in one sense of direction or the alternative sense so as to permit one person through it at a time the turnstile moving from one station or rest position to the next consecutive station. In such a turnstile the requirement arises that it should be reversible in sense of rotation when it is at rest at any one station. The invention has as its principal aim to eliminate a certain amount of malfunctioning which can be inconvenient and may be even dangerous, which will be enlarged upon below.

Application, Ser. No. 868109 now U.S. Pat. No. 3,602,350 describes and illustrates pawl-control mechanism embodied in turnstile mechanism and operating in accordance with the foregoing statement. The present invention is concerned with a refinement relating to the pawl itself in such apparatus. The description in the foregoing Patent Application is intended to be embodied herein by reference and it would therefore be repetitious to restate it in detail.

Turnstiles particularly as they may be used in public transport systems must be so contrived to minimize any human risk, inconvenience, or delay as far as possible. It is a defect of some existing mechanism that such a check pawl may overcarry when it is reached by a rest position and jam the next phase of rotation. In a turnstile this can be inconvenient and even dangerous, as the following narrative of an incident will show. Assume that a stream of passengers is passing through a turnstile, each one hard on the heels of the one ahead. Each person may reasonably assume that when he enters the turnstile it will be free, so he need hardly check his gait; but if in fact the turnstile is jammed when he enters it he may fall over it or at least be quite shocked by severe impact with the turnstile. This can arise if the check pawl jams the turnstile. The invention is concerned to obviate this inconvenience or risk.

According to the invention there is provided pawl controlled mechanism in which a series of teeth or abutments is to be engaged by a pawl which is reversible in its operative sense of direction which series is interrupted by one or more gaps to provide for pawl reversal, in which the pawl is pivotted for reversal and is resiliently urged towards a neutral position, further characterised by provision of second resilient means to act on the pawl with bias alternatively in one sense or the other of operational direction. In mechanism characterised as above the second resilient means is so constituted as to be substantially damped in its effect on the pawl; preferably this is accomplished by making the second resilient means in the form of a leaf spring made of a resilient synthetic plastics material with high internal damping of which a typical example is a Du Pont material "Adiprene" which is a synthetic plastics polyurethane material in the nature of a synthetic rubber. However, it is within possibility that where a plastics material is undesirable the second resilient means may be in the form of a laminated leaf spring with frictional interfaces to increase its self-damping properties.

A preferred form of the invention will now be described with reference to the accompanying drawings. In these

FIG. 1 is a scrap view which can readily be identified with FIG. 1 in the aforementioned application; where possible the same references are used.

FIG. 2 illustrates how the invention modifies the construction of FIG. 1 and shows the pawl in one rest position and

10 FIG. 3 is a view similar to FIG. 2 showing the alternative rest position.

In these Figures the toothed element of which the movements are to be controlled by the pawl is the rotatable member 1 with peripheral notches 2 and three peripheral gaps 4 disposed at 120° around the member 15 1. The member 1 is rotatable with the turnstile itself in order to control the latter. A double-acting reversible pawl 5 is shown mounted on a pivot spindle 6. The pawl is biassed to a neutral mid position as drawn in FIG. 1 in which the nose of the pawl 5 lies in one of the gaps 20 4. The nose 5A of the pawl 5 has two angled corners 5C so adapted that one of them will engage notches 2 as the turnstile and therefore the member 1 rotates. The pawl 5 is therefore operative in regard to either 25 25 sense of rotation of the turnstile. This ensures that starting from one of the 120° stations (as in FIG. 1) in whichever sense the turnstile is rotated so it is prevented from being turned from any substantial angle backwards until the next gap 4 is entered. It should be 30 30 observed that FIG. 1 is in fact unreal (as will be explained shortly) but it is here used mainly to show the close similarity of the present invention to that of the quoted Applications. The pawl is influenced towards the mid position in which it appears in FIG. 1 by a tension spring 12B which is tensed between a fixed post 35 35 12D and a pin 12E carried by the pawl 5.

By the invention there is added the second resilient means which is to act on the pawl in the form of a leaf spring 10 which is anchored at the pin 12D and which 40 40 bears (when the pawl is at rest) on one side or the other of the pin 12E. Which side it bears on is determined by the sense of operation direction last experienced by the pawl. Thus in FIG. 2 the arrow 21 is intended to indicate that the member 1 has last operated in an anti-clockwise direction, i.e. one in which the pawl 5 would have been rotated through a considerable clockwise angle from the position drawn. When in that operation 45 45 position it will be clear that the pin 12E was quite out of contact with the leaf spring 10. Such contact was, however, resumed when the pawl 5 fell into its rest position as shown in FIG. 2 in which position the leaf spring 10 contacted the right-hand side of the pin 12E. In that situation although the spring 12B tended to locate the pawl 5 in a strictly neutral position the opposing force due to the spring 10 causes the pawl to be 50 50 slightly biassed in its position, i.e. to take up a position of rest as shown in FIG. 2.

When, however, the direction of the arrow 21 is reversed (that is the member 1 has been turning clockwise) then of course the pawl 5 will have been operating in the sense contrary to the foregoing and the pin 12E having pushed its way past the spring 10 will return to the contrary side of the spring, the final rest position of the pawl 12 now being as seen in FIG. 3.

The high internal damping of the spring 10 brings the pawl 12 to rest as it approaches each rest position in a gentle manner so that the pawl does not tend to over-

run by its own momentum. This therefore ensures that the previously narrated type of incident will not occur. At the same time the operation is of course quick enough to take place between the passage through the turnstile of one person and the next.

It will thus be seen that by the addition of the second resilient means, that is to say the leaf spring 10 malfunctioning of the kind above mentioned is avoided.

I claim:

1. A pawl controlled mechanism comprising a pawl and a ratchet, said ratchet having a series of teeth interrupted by at least one gap and being supported for reversible movement, said pawl being supported for reversible pivoting movement and being positioned to engage said teeth to prevent substantial movement of said ratchet in one direction or the other and to enter said notch to permit reverse movement of said ratchet, and first means for resiliently urging said pawl to a neutral position with respect to said ratchet, said mechanism being further characterized by the provision of second means for resiliently biasing said pawl from its neutral position in one sense or the reverse sense when said

pawl enters said notch depending upon the previous direction of movement of said ratchet.

2. Mechanism according to claim 1 in which said second means has means for damping its effect on the movement of said pawl.

3. Mechanism according to claim 1 in which said second means is a leaf spring made of a resilient synthetic plastic material with high internal damping.

4. Mechanism according to claim 3 in which said first means is a tension spring and in which said leaf spring is positioned to engage said pawl when it enters said notch and urge said pawl in one sense or the reverse sense and is positioned to be disengaged from said pawl when the pawl engages said teeth.

5. Mechanism according to claim 1 in which said pawl has a nose of rectangular cross-section with two corners for alternating engaging said teeth depending upon the direction of movement of said ratchet and in which said notch has a pair of parallel sides adapted to engage corresponding corners of said nose.
